Primary Examiner—Cathron C. Brooks*Assistant Examiner*—Garth Rademaker(74) *Attorney, Agent, or Firm*—Hogan & Hartson, L.L.P.(57) **CLAIM**

The ornamental design for a photoconductor drum cartridge, as shown.

DESCRIPTION

This article is a photoconductor drum cartridge for a facsimile, a copier, a scanner, or a printer or a data processing machine of any combination thereof.

FIG. 1 is a perspective view of a photoconductor drum cartridge of the present invention;

FIG. 2 is another perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side elevational view thereof; and,

FIG. 8 is a left side elevational view thereof.
